UNITED STATES PATENT OFFICE.

ARTHUR J. ADAMS, OF BAY CITY, MICHIGAN, ASSIGNOR, BY MESNE ASSIGNMENTS, TO FERRIS-STEVENSON CORPORATION, OF BUFFALO, NEW YORK, A CORPORATION OF NEW YORK.

BABY-CARRIAGE OR PERAMBULATOR.

1,271,987.

Specification of Letters Patent.

Patented July 9, 1918.

Application filed May 22, 1917. Serial No. 170,166.

To all whom it may concern:

Be it known that I, ARTHUR J. ADAMS, a citizen of the United States, residing at Bay City, in the county of Bay and State of Michigan, have invented a new and useful Improvement in Baby-Carriages or Perambulators, of which the following is a specification.

The present invention is in the nature of a modification, or improvement, upon the structure disclosed in my application No. 170,165, filed on even date herewith.

The primary object of the present invention is to provide a baby carriage having the desirable qualities of the structure described and claimed in said co-pending application, the carriage-body being reversibly mounted upon the suspension frame, however.

The invention is illustrated in its preferred embodiment in the accompanying drawings, in which—

Figure 1 represents a broken side elevational view of a baby carriage embodying my invention, the axles being shown in section, and the wheels at one side removed; Fig. 2, a horizontal sectional view taken as indicated at line 2 of Fig. 1; Fig. 3, a broken vertical transverse sectional view taken as indicated at line 3 of Fig. 2; Fig. 4, a broken bottom plan view of the carriage-body and the frame, or turn-table, with which it is equipped, the swivel, or central vertical pivot, being shown in section; and Fig. 5, a broken vertical longitudinal section taken as indicated at line 5 of Fig. 3.

In the preferred construction, which is illustrated, A represents a running-gear frame; B, a suspension-frame suspended by means of coil-springs B'; and C, a carriage-body reversibly mounted on the frame B.

The running-gear frame, in the preferred construction, comprises a pair of axles 1; a pair of reach-members 2, the extremities of each reach-member being curved upwardly and toward each other to afford goose-necks, or suspension members, 2^a; and a handle 3 having the lower portion of its members curved forwardly and provided with substantially horizontal members 3^a, which afford supplemental reach-members disposed beneath the reach-members 2. The reach-members 2 have their intermediate portions bowed upwardly, and the extremities of said reach-members are so curved, in forming the goose-necks 2^a, as to harmonize with the

general design of the running-gear frame and afford a pleasing appearance.

Each axle is interposed between the rear portions of the reach-members 2 and the rear portions of the supplemental reach-members 3^a, being rigidly secured thereto by means of vertical rivet 4.

To the upper ends of the rivets 4 are connected diagonal braces 5, which extend rearwardly and forwardly and are united to the members of the handle 3. The front ends of the supplemental reach-members 3^a are flattened and rest upon the front axle, to which they are secured by rivets 6. Small brackets, or chairs, 6^a, are securely mounted on the front ends of the supplemental reach-members 3^a and the front axle, and have their intermediate or web-portions connected, by means of rivets 6^b, to the front portions of the reach-members 2. Braces 7 connect the extremities of the front goose-necks 2^a with the front axle.

The reach-members 2 and the supplemental reach-members 3^a are further connected, by clips or permanent clamps 8, disposed immediately in the rear of the rear axle. Each clip 8 is formed by bending a stout metal strap at an intermediate point to embrace the lower reach-member and uniting the upper ends of the clip to the reach-member 2, by means of a rivet 8^a. The intermediate portions of the members of each clip are spaced apart somewhat and united by a rivet 8^b, which serves to draw the members of the clip together and cause them to tightly embrace the tubular members 2 and 3^a.

The suspension frame B preferably comprises a pair of longitudinal metal bars 9, which are united near their extremities by diagonal braces 10, whose extremities are secured to the members 9 by means of rivets 10^a. The extremities of the members 9 are curved to afford eyes, which accommodate rivets, or bolts, 11, to which the adjacent ends of the substantially horizontal coil-springs B' are connected. The other ends of the coil-springs are connected to the goose-necks 2^a by means of rivets, or bolts, 12.

The carriage-body C has its lower side, or bottom, equipped with a metal frame, or turn-table, C', which preferably comprises a pair of longitudinal bars 13, which are connected by diagonal braces 14, whose extremities are joined, by rivets 14^a to the bars 13.

The bars 13 have extensions 13^a which are bent upwardly and attached to the bottom of the carriage-body.

The body-attached frame, or turn-table, 5 C', corresponds in size and shape with the suspension frame B, upon which it is mounted to turn.

The frames are firmly connected or swivelled together at a central point by a rivet, or 10 vertical pivot-member, 15, which holds the frame C' closely down against the suspension frame B, but permits the upper frame to be forcibly turned on the lower frame, when unlocked.

15 The frames are normally locked together by means of a transversely disposed spring-latch-bar 16, whose inner end is firmly secured to the lower end of the pivot-bolt 15. The outer end-portion of the latch-bar 16 20 extends under and past one of the longitudinal members 9 of the suspension frame B, thus affording a handle, or foot-piece, 16^a, by means of which the latch may be depressed. The outer end of the latchbar is 25 guided in its vertical movements by a guide-stud 17, which depends from the bar 9 and extends through a perforation in the bar 16. The latch-bar has rigidly applied thereto a clip 18, which is provided with upwardly- 30 extending latch-members, or bolts, 18^a, which are adapted to engage slots 19, with which each of the longitudinal members 13 of the upper frame C' are provided. When the carriage-body is facing forwardly, the 35 bits, or bolts, 18^a, engage the perforations 19 of one of the members 13; and when the carriage-body is reversed, the bolts engage the perforations of the other member 13. Thus, the carriage-body will be locked to the 40 suspension frame, regardless of which way the carriage-body faces.

The construction of the body C may be as desired. It is usual, however, to provide the rear portion of the body with an adjustable back 20.

As shown, the end-portions of the longitudinal bars 9 of the suspension turn-table frame B are struck downwardly, and the ends of the diagonal braces 10 are superposed upon the downwardly struck portions. Corresponding portions of the longitudinal bars 13 of the body-attached frame, or turn-table C', are struck upwardly, and the end-portions of the diagonal braces 14 underlie 55 the upwardly struck portions of the bars 13. The arrangement is such that the longitudinal bars 13 rest upon the bars 9, while the diagonal braces 14 rest upon the diagonal braces 10. In rotating the carriage-body upon the 60 central pivot 15, the braces 14 slide smoothly off of the braces 10 and over the bars 9 of the suspension frame B, the two frames being held closely in frictional engagement, nevertheless, by the rivet 15, which forms 65 the pivot about which the rotation takes

place. At the point where the brace-bars are pivotally connected, one of the lower brace-bars is bowed downwardly, and one of the upper brace-bars is bowed upwardly, so that the two frames B and C are forcibly held together under a certain resilience or pressure, owing to the fact that the rivet 15 which affords the pivot is short enough to effect this result. Thus, the upper frame C' is always firmly held against the suspension frame B, upon which it rests. 75

When it is desired to reverse the body, it is simply necessary to depress the latch-bar 16, as by means of the foot, and forcibly turn the body upon the axis 15. When the 80 body is in longitudinal alinement, the upper frame is locked to the lower frame, regardless of whether the carriage-body faces upwardly or rearwardly.

The foregoing detailed description has 85 been given for clearness of understanding only, and no unnecessary limitation should be understood therefrom, but the appended claims should be construed as broadly as permissible, in view of the prior art. 90

What I regard as new, and desire to secure by Letters Patent, is:

1. In a structure of the character set forth, the combination of a running gear-frame equipped at its ends with upwardly projecting suspension members, a suspension frame interposed between said suspension members and adapted to serve as a turn-table, spring suspension means including substantially horizontal tension springs between said suspension frame and said suspension members, and a body reversibly mounted on said suspension frame. 95

2. In a structure of the character set forth, the combination of a running gear-frame 105 provided at its front and rear portions with rigid suspension members, a horizontal suspension frame adapted to serve as a turn-table, horizontal coil-springs connecting said suspension frame to said suspension members, a body equipped with a frame adapted to serve as a turn-table, said body disposed wholly above the plane of said coil-springs, and a central swivel connection between said last-mentioned frames. 110

3. In a structure of the character set forth, the combination of a running gear-frame provided at its front and rear portions with rigid suspension members, a horizontal suspension frame adapted to serve as a turn-table, horizontal coil-springs connecting said suspension frame to said suspension members, a body disposed above the plane of said suspension frame and equipped with a frame 120 adapted to serve as a turn-table, a central swivel connection between said last-mentioned frames, and a latch-device adapted to secure said last-mentioned frames together. 125

4. In a structure of the character set forth, the combination of a running gear-frame, a 130

suspension frame comprising longitudinal bars and diagonal brace-bars secured thereto, coil-springs connecting said suspension frame to the running gear-frame, a rotatable

5 frame swiveled on said suspension frame and comprising longitudinal bars and diagonal brace-bars superposed on the corresponding bars of said suspension frame, and a body mounted on said rotatable frame.

10 5. In a structure of the character set forth, the combination of a running gear-frame, a suspension frame comprising longitudinal bars and diagonal brace-bars secured thereto, coil-springs connecting said suspension frame to the running gear-frame, a rotatable frame swiveled on said suspension frame and comprising longitudinal bars and diagonal brace-bars superposed on the corresponding bars of said suspension frame, and

20 means for locking the rotatable frame to the suspension frame.

6. In a structure of the character set forth, the combination of a running gear-frame equipped at its front and rear portions with spring supports, a suspension frame, substantially horizontal coil-springs connecting said suspension frame to said spring supports, a superposed rotatable frame, a body mounted on said rotatable

25 frame, and a latch-bar secured to said suspension frame and equipped with means for

engaging said rotatable frame, said latch-bar having an extension projecting past the suspension frame, by means of which the latch-bar may be released.

35

7. In a structure of the character set forth, the combination of a running gear-frame equipped with spring supports, a suspension frame, coil-springs interposed between said suspension frame and said spring supports, 40 a rotatable frame surmounting said first-named frame, a body mounted on said rotatable frame, a resilient latch-bar having its inner end secured to said suspension frame at a central point and having, near its outer 45 end, guide connection with said suspension frame, permitting vertical movement of the latch-bar, and a bolt carried by said latch-bar and extending through a perforation in said suspension frame and engaging a per- 50 foration in said rotatable frame.

8. In a structure of the character set forth, the combination of a running gear-frame, a horizontal frame mounted thereon and comprising longitudinal bars and diagonal 55 brace-bars, a rotatable frame comprising longitudinal bars and brace-bars corresponding with and surmounting said first-named bars, swivel connections between said brace-bars at a central point, and a body mounted 60 on said rotatable frame.

ARTHUR J. ADAMS.
